US00D777796S

(12) **United States Design Patent** (10) **Patent No.:** **US D777,796 S**
(45) **Date of Patent:** **** Jan. 31, 2017**

(54) **ROCK DUST BLOWER**

- (71) Applicant: **Hafco Foundry and Machine Company**, Midland Park, NJ (US)
- (72) Inventors: **Michael J. Fornaci**, Oakland, CA (US); **William J. Fornaci**, Hawthorne, NJ (US); **John R. Rodriguez**, Rockaway, NJ (US); **Basil J. Fornaci**, Hawthorne, NJ (US); **Istvan J. Kiss**, Oakland, NJ (US)
- (73) Assignee: **Hafco Foundry and Machine Co., Inc.**, Midland Park, NJ (US)
- (**) Term: **14 Years**
- (21) Appl. No.: **29/495,001**
- (22) Filed: **Jun. 26, 2014**

Related U.S. Application Data

- (63) Continuation of application No. 29/453,848, filed on May 3, 2013, now Pat. No. Des. 752,111, which is a continuation-in-part of application No. 29/404,223, filed on Oct. 18, 2011, now Pat. No. Des. 681,684.

(57) **CLAIM**

The ornamental design for a rock dust blower, as shown and described.

DESCRIPTION

- FIG. 1 is a front elevational view of a rock dust blower showing our new design;
FIG. 2 is a rear elevational view of the rock dust blower shown in FIG. 1;
FIG. 3 is a right side elevational view thereof;
FIG. 4 is a left side elevational view thereof;
FIG. 5 is a bottom plan view thereof;
FIG. 6 is a another front elevational view of a rock dust blower in an alternate environment;
FIG. 7 is a rear elevational view of the rock dust blower shown in FIG. 6;
FIG. 8 is a right side elevational view thereof;
FIG. 9 is a left side elevational view thereof; and,
FIG. 10 is a bottom plan view thereof.

1 Claim, 10 Drawing Sheets
